MACHINE FOR TYPEWRITING

Elmer L. Wise, Bridgeport, Conn., assignor to
Underwood Elliott Fisher Company, New York,
N. Y., a corporation of Delaware

Application June 28, 1941, Serial No. 400,233

7 Claims. (Cl. 197—3)

This invention relates to typewriting machines and typewriting and accounting machines of the so-called Elliott Fisher or flat platen type and more particularly to clamping devices for clamping cards and similar work sheets on the platen.

Certain objects of the invention are to improve the construction and mode of operation of work sheet clamping devices and to produce a clamp construction by which a work sheet of less width than the platen may be clamped along two or more edges of the sheet.

Another object of the invention is to produce a combination of work clamping device and gauging means by which a work sheet of less width than the platen may be gauged and clamped along two or more edges.

With the above and other objects in view, the invention consists in a mechanism embodying the novel and improved features, constructions and combinations of parts hereinafter described and particularly pointed out in the claims, the advantages of which will be readily understood and appreciated by those skilled in the art.

The invention will be clearly understood from the accompanying drawing illustrating the invention in its preferred form and the following detailed description of the construction therein shown.

In the drawing:

Fig. 1 is a plan view illustrating the platen frame and platen of a typewriting or typewriting and accounting machine of the Elliott Fisher type provided with work clamping mechanism embodying the invention.

Fig. 2 is a detail plan view on an enlarged scale illustrating a portion of the mechanism shown in Fig. 1 with a card located in operating position with relation to the card clamping mechanism.

Fig. 3 is a view in front elevation, partly in vertical section, illustrating the mechanism shown in Fig. 2 with the platen in elevated position.

Fig. 4 is a view similar to Fig. 3 showing the platen in depressed position, and

Fig. 5 is a detail sectional view taken substantially on the line 5—5 of Fig. 1.

The invention is illustrated as applied to a typewriting machine or typewriting and accounting machine of the Elliott Fisher type such as that illustrated and described in the patent to Foothorap, No. 1,904,127, dated April 18, 1933. The machine comprises a substantially rectangular platen frame indicated as a whole at 2 and provided with substantially parallel side bars or

rails indicated at 4 connected by cross bars, certain of which are indicated at 6. The machine is provided with the usual line space frame mounted upon the side rails 4 of the platen frame for forward and rearward movement. The machine is further provided with the usual type carriage supported upon front and rear rails forming parts of the line space frame for movement in letter spacing direction and return.

10 Mounted in the platen frame is the usual substantially flat platen indicated at 7, carried on suitable supporting links or other supporting devices and arranged to be moved vertically in the platen frame by a suitable manually operated and controlled mechanism, such as a spring and treadle mechanism.

All of the parts above briefly described preferably have substantially the same construction as the corresponding parts of the machine illustrated and described in said Foothorap patent. It is not considered necessary to disclose in this application the line space frame, together with its operating mechanism or the type carriage, since these mechanisms are sufficiently disclosed in the above Foothorap patent.

In Fig. 1 is illustrated a type bar indicated at 8, the type bar being shown in its lowered position for engaging the type with the work. The platen may be supported and operated by mechanism substantially the same as that disclosed in the patent to Foothorap No. 1,596,420, dated August 17, 1926, or by any other suitable mechanism by which it may be moved vertically to clamp and release the work sheets.

35 The clamping mechanism for clamping the work sheets on the platen comprises a clamping strip indicated at 9, secured to the left hand platen rail 4 and extending forwardly and rearwardly with relation to the platen, this strip being mounted in a groove in the rail and arranged to extend from the rail a short distance over the platen as shown in the drawing. This strip is terminated a considerable distance from the front end of the platen. Just forwardly of the forward end of the clamping strip 9, the clamping plate 10 is mounted on the left rail 4 of the platen frame and is arranged to extend laterally over the platen for a substantial distance toward the fore-and-aft central line of the platen. The clamping plate 10 is provided with an attaching portion or base 11 which is mounted in a groove in the left hand rail 4 in substantially the same manner as the strip 9. To support the right hand portion, Figs. 1 and 2, of the clamping plate 10, said portion of the plate is fixed to the upper end

of a rod 12 extending from the plate downwardly through an opening 14 in the platen. In order to support the rod, a bar 16 is attached, at its ends, to the under sides of the cross bars 6 of the platen frame and the lower end portion 18 of the rod 12 is threaded and passes through an opening in said bar. To hold the rod from axial movement with relation to the bar, nuts 20 are threaded upon the portion 18 of the rod and are drawn up tight against the bar 16.

The left hand rail 4 constitutes a gauge for locating the left hand edge of a work sheet introduced between the platen and the clamping plate 10. In order to locate the right hand edge of said sheet with relation to the clamping plate and platen, a gauge 22 is mounted upon the upper end of the rod 12 between a shoulder 24 on the rod and the clamping plate 10. The gauge 22 is preferably circular in cross section and is made somewhat larger in diameter than the rod 12, the gauge fitting into an enlarged portion of the opening 14 in the platen when the platen is raised. As shown, the upper end portion 26 of the rod 12 is threaded and the gauge 22 is correspondingly threaded to fit on the rod and is screwed up tight against the shoulder 24. The portion 26 of the rod is also threaded into the plate 10 and the extreme end thereof is riveted over, as clearly shown in Fig. 4.

The card or other work sheet is introduced between the platen and the clamping plate 10 substantially in the position shown in dot and dash lines and indicated at C in Fig. 2. When in this position, the forward portion of the clamping strip 9 and the portion of the clamping plate 10 forwardly thereof, will clamp the left hand marginal portion of the card and the rear marginal portion 28 of the clamping plate 10 will clamp the work sheet forwardly of the printing line. In order to clamp the work sheet to the right of the printing point or line, the clamping plate 10 is provided with an extension 30 projecting rearwardly from the body of said plate as shown in Figs. 1 and 2. This extension terminates in an edge 32 located some distance to the left of the gauge 22. Thus when the card or other work sheet is located beneath the clamping plate 10 with its right hand edge in engagement with or relatively close to the gauge 22, the extension 30 will extend over the right hand marginal portion of the work sheet, as shown in Fig. 2, and will clamp the same to the platen when the platen is raised.

The rear edge of the body of the clamping plate 10 which engages a work sheet in front of a typing line, is beveled as shown in Fig. 5 to avoid contact of the type heads therewith.

By means of the clamping strip 9 and the clamping plate 10 with its extension 30, a card or other work sheet, introduced between the clamping plate and the strip and the platen, may be clamped on both sides of and in front of the printing or typing line. The adjustable connection between the lower end of the rod 12 and the bar 16, enables the vertical position of the right hand end portion of the clamping plate 10 to be accurately adjusted vertically to locate the clamping plate parallel with the platen.

Having explained the nature and object of the invention and having specifically described a construction embodying the invention in its preferred form, what is claimed is:

1. In a machine of the class described having a substantially rectangular platen frame comprising side rails and cross bars connecting said

side rails and a substantially flat platen mounted for vertical movement in said frame; a clamping strip attached to one of the side rails of the platen frame and arranged to engage a work sheet at one side of the typing point, a clamping plate fixed to the latter side rail and extending from the same over the platen to a point spaced from the other side rail and arranged to clamp the work sheet in front of the typing point and an extension on the inner portion of said plate projecting rearwardly from the body of the plate and spaced from each side rail to clamp the work sheet at the other side of the typing point.

2. In a machine of the class described having a substantially rectangular platen frame comprising side rails and cross bars connecting said side rails and a substantially flat platen mounted for vertical movement in said frame; a clamping plate attached to one of the side rails of the platen frame and extending therefrom a substantial distance over the platen toward the central portion of the same and a gauge attached to the inner portion of said plate and extending into the adjacent portion of the platen for engagement with the inner edge of a work sheet introduced between said clamping plate and the platen.

3. In a machine of the class described having a rectangular platen frame comprising side rails and cross bars connecting said side rails and a substantially flat platen mounted for vertical movement in said frame; a clamping plate attached to one of the side rails of the platen frame and extending therefrom over the platen a substantial distance toward the central portion thereof, a bar attached to the platen frame beneath the platen, a rod extending through an opening in the platen and supported at its lower end by a connection to said bar and a connection between the upper end of the rod and said clamping plate to support said plate.

4. In a machine of the class described having a rectangular platen frame comprising side rails and cross bars connecting said side rails and a substantially flat platen mounted for vertical movement in said frame; a clamping plate attached to one of the side rails of the platen frame and extending therefrom over the platen a substantial distance toward the central portion thereof, a bar attached to the platen frame beneath the platen, a rod extending through an opening in the platen, an adjustable connection between the lower end of said rod and said bar to support the rod for longitudinal adjustment and a connection between the upper end of the rod and said clamping plate to support the plate.

5. In a machine of the class described having a substantially rectangular platen frame comprising side rails and cross bars connecting said rails and a substantially flat platen mounted for vertical movement in said frame; a stationary clamping plate secured to and extending inwardly from one of the side rails of the platen frame transversely of the platen toward the central portion thereof and terminating short of the other side rail, said clamping plate having a portion for engaging a work sheet in front of the typing line and means attached to said frame and to the inner portion of said plate for fixedly supporting said inner portion.

6. In a machine of the class described having a substantially rectangular platen frame comprising side rails and cross bars connecting said rails and a substantially flat platen mounted for ver-

tical movement in said frame; a clamping plate secured to one of the side rails and extending inwardly therefrom toward the central portion of the platen, a gauge fixed to the under side of the clamping plate adjacent the inner end of the plate for engaging the edge of a side margin of the work sheet to locate the same laterally on the platen and a rearward extension on the plate terminating in a marginal portion arranged to extend over the margin of the work sheet engaged with said gauge.

7. In a machine of the class described having a substantially rectangular platen frame com-

prising side rails and cross bars connecting said rails and a substantially flat platen mounted for vertical movement in said frame; a fixed clamping plate secured to one of the side rails and extending therefrom transversely over the platen and terminating in spaced relation to the other side rail, said plate having a body portion for engaging the work sheet in front of the typing line and an extension projecting rearwardly on the side thereof opposite the former rail for engaging the work sheet at one side of the typing line.
